US0D1022733S

(12) **United States Design Patent** (10) **Patent No.:** **US D1,022,733 S**
(45) **Date of Patent:** **** Apr. 16, 2024**

(54) **LIDAR SENSOR FOR A VEHICLE**

(71) Applicant: **VOLVO CAR CORPORATION**,
Gothenburg (SE)

(72) Inventor: **Sebastiano Ciarcia**, Västra Frölunda
(SE)

(73) Assignee: **VOLVO CAR CORPORATION**,
Gothenburg (SE)

(**) Term: **15 Years**

(21) Appl. No.: **29/856,906**

(22) Filed: **Oct. 18, 2022**

(30) **Foreign Application Priority Data**

Apr. 21, 2022 (EM) 008944664-0007

(57) **CLAIM**

The ornamental design for a LIDAR sensor for a vehicle, as shown and described.

DESCRIPTION

FIG. 1 is a front view of a LIDAR sensor for a vehicle showing my new design;

FIG. 2 is a rear view thereof;

FIG. 3 is a front and left side perspective view thereof;

FIG. 4 is a rear and left side perspective view thereof;

FIG. 5 is a right side view thereof;

FIG. 6 is a left side view thereof;

FIG. 7 is a top view thereof; and,

FIG. 8 is a bottom view thereof.

1 Claim, 8 Drawing Sheets
